UNITED STATES PATENT OFFICE

1,970,418

SWITCH ATTACHMENT FOR CAMERAS AND
THE LIKE

John T. Fagan, Cleveland Heights, Ohio, assignor to General Electric Company, a corporation of New York

Application June 8, 1932, Serial No. 616,061

2 Claims. (Cl. 67—29)

My invention relates to photography and more particularly to switching means for operation in synchronization with camera shutter movement. Still more particularly, my invention relates to a switching device which can be easily applied to the camera shutter cable release. When pictures are taken with the use of flash lamps and the like, the opening of the shutter and the operation of the flash lamp should be properly timed. This is particularly true when moving objects are to be taken in only partial darkness and the shutter cannot therefore be opened before the illuminant is set off. One object of my invention is to provide a portable switching device for closing an electrical circuit which can be attached to the usual cable shutter control and be operated thereby. Various features and advantages of my invention will appear from the following description of a species thereof and from the accompanying drawing.

Now referring to the drawing, Fig. 1 is a perspective view of the device of my invention; Fig. 2 is a section through said device; Fig. 3 is a plan view of the body portion of my device; and

Fig. 4 is a diagram showing my device in use.

The switch 10 comprises, as shown in the drawing, a body portion of insulating material such as hard rubber or the like to which is attached cap 11 by screws 12 and 13. A raised boss 14 forms part of the cap 11 and receives the head 15 of the cable release pin 16 which is inserted through opening 17 in the side of said boss and its tapered portion 18 is held against the edge of opening 19 in the boss by plate 20 of conductive material preferably metal, which is pressed by spring 21 located between the latter and the body portion 10 of the switch. Although the specific shutter release device shown, which is of a well known manufacture, is particularly suited for my device, I am aware that my device may be modified for use with other shutter release devices. The operation of the shutter release device is as usual as the release pin 16 is now operated by pressure on the switch which takes the place of its head 15. The electrical function of the switch is brought into play by pressure exerted thereupon after the movement of the release pin 16 has been arrested upon its reaching the limit of its motion as continued pressure will then force lugs 23 and 24 (Fig. 3) extending from metal terminal straps 25 and 26 respectively into engagement with the plate 20. During the forepart of the pin motion the switch is not operated as the resistance of spring 21 is greater

than the force required to move said pin. The electrical circuit is therefore closed by the bridging of the terminals 25 and 26 by the plate 20 after the shutter has been released, and it has been found that such operation allows the shutter sufficient time to be fully opened before the illuminant flashes. Washer 27 serves to insulate cap 11 from bars 25 and 26. The circuit shown in Fig. 4 includes the switch 10 with its terminals 25 and 26 connected respectively to a battery 28 and a flash lamp 29.

What I claim as new and desire to secure by Letters Patent of the United States is:

1. A switch of the class described for use with the shutter control pin of a camera, said switch comprising a body portion having a pair of terminals held therein and having a cap mounted thereon adapted to engage the underside of a head on said control pin and a conductive member resiliently mounted with respect to said body in contact with the head on said control pin and adapted to be pushed into contact with said terminals by said control pin.

2. A switch of the class described for use with the shutter control pin of a camera, said switch comprising a body portion having a pair of terminals held therein and having a cap mounted thereon adapted to engage the underside of a head on said control pin, a conductive member adapted to engage the head of said control pin, and a spring located between said conductive member and said body portion of said switch whereby said conductive member is caused to be pressed into contact with said terminals by said control pin.

JOHN T. FAGAN.
